CLAIM

The ornamental design for a phone case, as shown and described.

DESCRIPTION

FIG. 1 is a left, top, front perspective view of a phone case showing our new design;

FIG. 2 is a left, top, front perspective view of the phone case of FIG. 1;

FIG. 3 is a right, top, rear perspective view of the phone case of FIG. 1;

FIG. 4 is a front elevation view of the phone case of FIG. 1; FIG. 5 is a rear elevation view of the phone case of FIG. 1; FIG. 6 is a right side elevation view of the phone case of FIG. 1;

FIG. 7 is a left side elevation view of the phone case of FIG. 1;

FIG. 8 is a top plan view of the phone case of FIG. 1; and, FIG. 9 is a bottom plan view of the phone case of FIG. 1. The broken lines showing portions of the design in all figures are included for the purpose of illustrating environment and unclaimed features and forms no part of the claimed design.

1 Claim, 7 Drawing Sheets
